UNITED STATES PATENT OFFICE.

JOHN M. SNYDER, OF YORK, PENNSYLVANIA.

COMBINED BENCH AND MUSIC CABINET.

Application filed June 27, 1921. Serial No. 480,759.

To all whom it may concern:

Be it known that I, JOHN M. SNYDER, a citizen of the United States, residing at York, in the county of York and State of Pennsylvania, have invented certain new and useful Improvements in Combined Benches and Music Cabinets, of which the following is a specification.

My said invention relates to a combined bench and music cabinet for use with a piano, organ or like musical instrument and it is an object thereof to provide a convenient receptacle for sheet music or music rolls.

Referring to the accompanying drawings which are made a part hereof and on which similar reference characters indicate similar parts,

Figure 1 is a perspective of my device,

Figure 2 a vertical longitudinal section, 20 and

Figure 3 a partial horizontal section of a modified form.

In the drawings reference character 10 indicates the top or seat of the bench which 25 may be of conventional form and which is provided with sides consisting of parts 11 and 12 and end pieces 13, the parts 12 and 13 forming supports for the bench.

A drawer 14 is supported in any convenient manner by the sides and top and forms 30 a receptacle for sheet music. In Figure 2 I have indicated at 15 a pair of brackets attached to the top and engaging grooves in the sides of the drawer.

At opposite ends of the device there are 35 supported a pair of receptacles for sheet music. Each receptacle is pivoted near the bottom of an aperture in the end member 13, on hinges 16 and is freely swingable into 40 an outer position as in Figure 1, or an inner position, as in Figure 2, being limited by stops 17 which engage with the adjacent parts of member 13, the latter being cut away to provide an opening for the receptacle which opening is preferably but not necessarily rectangular and is closed by the receptacle in its inner position. The receptacles are provided with handles 18 by 45 which they may be conveniently opened by a person seated on the bench who may then withdraw sheets of music from the several compartments of the receptacles or replace them therein. The compartments referred to are formed as indicated by partitions 19

50 of which any desirable number may be provided.

The inward movement of the receptacles is limited by stops 20 which engage with their lower inner corners. Upright members 21 are also shown in Figure 2 which act as closures to prevent access of dust to the receptacles and which may be relied on to limit the inward movement of the same. Preferably both the closures 21 and the stops 20 are provided, but either one may be omitted if desired. At their upper ends the receptacles are rounded as shown to secure ease of movement, and to present a good appearance in their outer position.

The partitions 19 may be made of cardboard loosely held in place as by grooves at the sides of the receptacle and may carry letters or figures so that they can be arranged in alphabetical or numerical order. The music can then be arranged by titles or 75 by years or in any other order desired, in the various compartments and can easily be kept in such predetermined order.

In the modified form of Figure 3 the bench is similar to that of Figures 1 and 2 except 80 that in place of the partitions 19 there are provided partitions extending both longitudinally and transversely of the receptacle whereby the same is divided into a plurality of spaces 22 adapted for holding music 85 rolls.

One or both receptacles may be formed as in Figure 3 for music rolls and drawer 14 may be omitted if desired. A desirable arrangement consists of two end receptacles 90 arranged to hold rolls for use in an automatic player, and a drawer 14 to hold sheet music. Various other changes may obviously be made within the scope of my invention as defined by the appended claims.

Having thus fully described my said invention, what I claim as new and desire to secure by Letters Patent is:

1. A music bench comprising a top adapted to be used as a seat, end supporting members with walls at the sides and back only, receptacles adapted to receive music, pivoted along their lower front edge and adapted to form bottom and front walls for the supporting members, the rear walls of the 105 receptacles being adapted to rest against the said back walls of the supporting members, substantially as set forth.

2. A music bench comprising a top adapted to be used as a seat, supporting members spaced apart with a free open space between them and located under the respective

2
ends of said seat, said end supporting members having walls at the sides and back and normal open fronts, receptacles mounted in said open fronts and pivoted along their lower front edges and adapted to fit within and close said open fronts resting against the back walls of the supporting members, substantially as set forth.

In witness whereof, I have hereunto set my hand and seal at York, Pennsylvania, ¹⁰ this 20th day of June, A. D. nineteen hundred and twenty-one.

JOHN M. SNYDER. [L.S.]

Witnesses:

HARRY E. SNYDER,
H. P. KELLER.
